UNITED STATES PATENT OFFICE.

FREDERICK E. PRETAT, OF WATERBURY, CONNECTICUT, ASSIGNOR TO INTERNATIONAL SILVER CO., OF MERIDEN, CONNECTICUT, A CORPORATION OF NEW JERSEY.

DESIGN FOR A HANDLE FOR SPOONS, FORKS, OR SIMILAR ARTICLES.

● 45,309.

Specification for Design.

Patented Feb. 24, 1914.

Application filed December 29, 1913. Serial No. 809,428. Term of patent 7 years.

To all whom it may concern:

Be it known that I, FREDERICK E. PRETAT, a citizen of the United States, residing at Waterbury, in the county of New Haven and State of Connecticut, have invented a new, original, and ornamental Design for a Handle for a Spoon, Fork, or Similar Article, of which the following is a specification, reference being had to the accompanying drawing, forming part thereof.

Figure 1 is a face view of a spoon, fork or similar article, showing my new design. Fig. 2 is a detail perspective view.

I claim:

The ornamental design for a handle for a spoon, fork or similar article, as shown.

FREDERICK E. PRETAT.

Witnesses:

G. C. WELTON,
E. A. BERNHARD.
